Primary Examiner — Barbara Fox*Assistant Examiner* — Jennifer L Rempfer(74) Attorney, Agent, or Firm — Nicholas A. Kees; Godfrey & Kahn, S.C.(57) CLAIM

The ornamental design for an soccer ball infant bodysuit, as shown and described.

DESCRIPTION

FIG. 1 is an isometric view of an soccer ball infant bodysuit, showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The features shown in broken lines in the various drawing figures are used to show environmental structure, and form no part of the invention.

1 Claim, 5 Drawing Sheets---
